FOLDING CIGARETTE BOX WITH ASH RECEPTACLE

Clyde A. Peel, Richard O. Peel, and Donald G. Peel,
all of 17080 Fruitport Road, Spring Lake, Mich.

Filed Mar. 30, 1959, Ser. No. 802,874

15 Claims. (Cl. 131—238)

This invention relates to improvements in folding cigarette box with ash receptacle. The principal objects of this invention are:

First, to provide a box or container for cigarettes in the form of a pocket package in which a side of the box may be opened to provide an ash receptacle without destroying the cigarette retaining characteristics of the package.

Second, to provide a box type cigarette package with a swinging top and a collapsible wall which can be pulled out after the top is open to provide a convenient ash receptacle separate from the cigarette containing portions of the box.

Third, to provide a cigarette box having a collapsible and extendable ash receiving pocket which can be assembled and erected on existing cigarette box forming machines.

Fourth, to provide a modified form of cigarette box which can be erected from a single integral blank of light cardboard or box board to provide a cigarette containing section and a collapsible and extensible ash receiving receptacle.

Fifth, to provide a cigarette box capable of being opened and closed a number of times in the normal use of a cigarette package and further provided with extensible walls forming an ash receptacle which can be opened when the top of the box is opened and which is retained in closed position by the box top when the box is closed.

Other objects and advantages of the invention will be apparent from a consideration of the following description and claims. The drawings, of which there are three sheets, illustrate two highly practical forms of the package and three methods of erecting them.

Fig. 1 is a perspective view of a preferred form of the cigarette box of the invention with the top and the ash receiving receptacle in open position.

Fig. 2 is a plan view of the box board blank from which the package shown in Fig. 1 is assembled.

Fig. 3 is a plan view of the insert blank which is folded into the blank shown in Fig. 2 in assembling the finished package. It is pointed out that the blanks shown in Figs. 2 and 3 are not drawn to the same scale.

Fig. 4 is a perspective exploded view of the box and blanks shown in Figs. 1 to 3 in partially assembled and erected position.

Fig. 5 is a plan view of a modified form of blank capable of being erected into a box containing an integral ash receptacle.

Fig. 6 is a perspective view of an erected cigarette box formed from the blank shown in Fig. 5 with the ash receptacle thereof in open operative position.

Fig. 7 is a fragmentary front elevational view of the lower corner of the box shown in Fig. 6 with successive layers of the box broken away in cross section to show the internal construction of the erected box.

Fig. 8 is an exploded perspective view showing a modified way of erecting the blanks shown in Figs. 1 and 3.

2

Fig. 9 is a fragmentary side elevational view of a package erected as in Fig. 8 with parts broken away.

The cigarette box and blank shown in Figs. 1 and 2 is made of light weight cardboard or box board of the type currently used in crush proof pocket packages or boxes for cigarettes. The box and the blank shown in Fig. 2 have an integral back wall 1, bottom wall 2, front wall 3 and top wall 4. A short back cover wall portion 5 is connected between the top wall 4 and the back wall 1 and all of these walls are hingedly or bendably connected along fold lines indicated by the dotted score lines 6. The sides of the back wall 1 are hingedly connected at 7 to inner side wall flaps 8 which have downwardly inclined upper edges 9 formed by full cuts or slits in the blank.

15 Above the upper edges 9 the continuation of the inner side wall flaps 8 form inner cover end flaps 10 hingedly connected at 11 to the sides of the back cover wall portion 5. The upper edges of the inner cover side flaps 10 are hingedly connected at 12 to cover tuck flaps 13 separated from the top wall 4 by the slits 14.

The upper edge of the top wall 4 is hingedly connected to a front cover flap 15 having outer end cover flaps 16 attached to its ends and an inner front cover flap 17 attached to its upper edge. The upper edges of the outer end cover flaps 16 are inclined downwardly parallel to the upper edges 9 of the inner side wall flaps 8 to abut thereagainst when the package is erected. The front cover flaps 15 and 17 and the outer end cover flaps 16 are provided with adhesive coatings indicated generally at 30 18 and the cover portion of the box is folded and erected into a swingable cover generally indicated at 19 in Fig. 1 in a well known manner so that the details of the cover form no part of the present invention except as they coact with the other elements of the box and package to be described.

The lower edges of the inner side wall flaps 8 are hingedly connected at 20 to bottom tuck flaps 21 separated from the remainder of the blank by cuts or slits 22. The sides of the front wall panel 3 are hingedly connected 40 to outer side wall flaps 23 which are downwardly inclined on their lower edges as at 24 to be parallel with the upper edges 9 of the inner side walls 8 when erected. The outer side walls flaps are partially severed from the front wall 3 by a series of interrupted slits 24 forming a frangible and bendable connection between the front wall and the outer side walls.

The ends of the bottom wall 2 are provided with an adhesive coating 25 which coacts with and secures the undersides of the tuck flaps 21 of the bottom wall when the 50 box is erected. The outer side walls 23 are provided with an adhesive coating 26 which adheres to and connects the outer side walls to the outsides of the inner side walls 8 when the box is erected. The blank thus far described can be erected by existing machinery to form 55 an ordinary five walled box with a swingable box shaped cover.

In order to provide the desired ash receptacle in the box formed by the foregoing blank a separate insert blank shown in Fig. 3 is provided. The insert blank 60 has an inner front wall 27 hingedly connected at the bottom to an outer front wall 28. The upper edge of the inner wall 27 has a central recessed edge 29 and the lower edge of the outer panel 28 has a correspondingly shaped tongue 30, and it will be noted that a continuous series of insert blanks can be cut from a sheet of stock 65 without waste. The tongue 30 is desirably provided with a V-shaped notch 31 which is disposed in upwardly opening position when the box is assembled. The side edges of the inner insert wall 27 are foldably connected at 32 to inner side flaps 33 and the side edges of the front insert wall 28 are connected by the fold lines 34 with the outer side flaps 35. It is pointed out that the inner in-

sert wall 27 and its side flaps 33 are longer than the outer insert wall 28 and its side flaps 35 so that as the outer front wall 28 is folded upwardly against the inner wall 27 and the side flaps 33 and 35 folded rearwardly into lapped relation, the insert blank forms a channel shaped cross section with the notched tongue 30 and the upper edges of the side flaps 35 disposed below the upper edges of the inner wall 27 and the side flaps 33. The lower edges of the side flaps 35 are inclined upwardly as at 351 when erected.

The outer wall 28 of the insert blank and its tongue 30 are longer than the front wall 3 of the box blank, but the walls 3 and 28 are of approximately the same width and the side flaps 23 and 35 of the two blanks are of approximately the same width. In assembling the insert blank into the outer box the insert blank is folded into channel shape as described and is placed over the back wall 1 of the box blank and the inner side walls 8 of the box blank are folded up into lapped relation over the outer sides of the insert flaps 35. Where the inner side flaps 8 of the box blank extend above the outer flaps 35 and below the inclined edges 351 of the side flaps 35, registering areas 36 and 361 of adhesive are provided on the ends of the box flaps 8 and the inner flaps 33 of the insert. These adhesive areas secure the insert blank to the partially erected box while leaving the front wall 28 and its side flaps 35 of the insert blank free to hinge forwardly of the box. If desired, the lower cut away 351 and adhesive 361 can be omitted.

After the insert blank is partially assembled into the box blank which operation can be performed over a packet of cigarettes prewrapped in an inner foil wrapper such as is indicated at 37 in Fig. 1, the bottom wall 2 and front wall 3 of the box blank are folded successively upwardly to seal the bottom wall 2 and its adhesive coating 25 to the undersides of the tuck flaps 21 and to seal the front wall 3 to the outer side of the outer wall 28 of the insert blank. For this purpose the inside of the front wall 3 is provided with an adhesive coating 38. The outer side walls 23 are then folded rearwardly over the inner side walls 8 and secured thereto by the adhesive coating 26. The tongue 30 on the insert blank projects above the front wall 3 and is retained behind the swingable cover 19 when the cover is closed over the packet 37 in the usual fashion.

In the closed and sealed condition of the box the frangible connection formed by the interrupted slits 241 and the overlapped engagement of the cover 19 with the tongue 30 holds the box in securely erected position for shipment and sale of the package. When the purchaser or user opens the cover 19 in the usual manner the tongue 30 and the upper edge of the front wall 8 are exposed so that the front wall can be pulled forwardly breaking the frangible connection between the front wall and the outer side walls as at 39. The outer side flaps 35 of the insert blank slide between the inner side walls 8 of the box and the inner side flaps 33 of the insert while the adhesive areas 36 hold the side flaps 33 and the rear wall of the insert blank in assembled relation. A wedge or hopper shaped pocket is thus formed between the front and rear walls of the insert blank which can be used as an ash tray. The notch 31 forms a convenient support for resting a cigarette on the box. The package can be reclosed by pushing in the front wall 8 and reclosing the cover 19 over the tongue 30 in which position the box continues to function as a convenient crush proof carton for the remaining cigarettes contained therein.

Desirably the opposed surfaces of the insert blank walls 27 and 28 and the side flaps 35 are rendered fire proof to resist the temperature of hot ashes and cigarette butts. This may be accomplished by applying a metal foil cover indicated conventionally at 40 to the insert blank or by otherwise treating the blank with a suitable fire proofing material. The ash receptacle formed by

the insert blank will not only function to receive cigarette ashes but can be used to extinguish burning cigarette butts simply by closing the front walls 3 and 28 against the rear wall 27; the burning end of the cigarette butt 5 can be crushed and air excluded therefrom. Ashes and the extinguished butt can, of course, be emptied from the receptacle as convenient to the user.

The modified form of cigarette box or carton shown in Figs. 5 to 7 consists of a single integral blank in which 10 the back wall 41 and bottom wall 42 are connected to the front wall 43 of the box proper as in the first form of the invention. The upper edge of the blank is provided with the same top wall 44, cover back wall 45 and cover forming flaps which will not be redescribed. 15 The sides of the back wall 41 are provided with side wall flaps 46 which in this instance form the outer side walls of the erected box. Tuck flaps 47 on the lower ends of the flaps 16 fold inwardly and are secured to an adhesive coating 48 on the bottom wall 42.

Secured directly to the edge of the front wall 43 along the fold line 49 which forms the upper front edge of the box is an outer receptacle wall 50 with side receptacle flaps 51 on its edges. The upper edges of the flaps 51 are inclined downwardly and rearwardly as at 52 when the carton is erected. The bottom edges of the flaps are inclined upwardly as at 521. Secured to the opposite edge of the front receptacle wall 50 along the fold line 53 is an inner receptacle wall 54 having a notched or recessed edge 55 disposed along the upper 20 edge of the front wall when the box is erected. Side flaps 56 on the sides of the receptacle wall 54 fold inside of the outer side wall flaps 46 on the back wall 41 of the box and are secured thereto by the coating adhesive areas 57 and 571 when the box is erected.

In erecting the box from the blank shown in Fig. 5 the panel 50 is folded over into lapped relation with the panel 43 and secured thereto by the lines of adhesive 58.

The panel 54 which forms the inner receptacle wall is folded oppositely onto the back of the panel 50 and the 25 side flaps 51 and 56 are folded rearwardly in lapped relation along the sides of the package after which the outer side wall flaps 46 are folded upwardly and secured by the adhesive areas 57 and 571 which are located at the upper and lower edges of the flaps 46. Thus in the 30 erected position of the box shown in Fig. 6 the front receptacle forming panel 50 secured to the outer panel 43 of the box is tiltable about the forward edge of the bottom wall 42 with the side receptacle forming flaps 51 sliding between the flaps 56 and 46. The end panel 54 and its side flanges 55 which fold into the box to form the 35 forward cigarette retaining wall are longer than the receptacle forming walls 43 and 50 to project upwardly into the swinging cover when the box is erected. The upper edges of the panels 43 and 50 project upwardly 40 above the lower edge of the cover when the box is closed and hold the ash receptacle panels in closed position.

Desirably the opposed faces of the ash receptacle panels are provided with a fire proof coating or surface 59 which is applied to the reverse side of the panels 50 and 54 as viewed in the blank in Fig. 5.

Both forms of the box illustrated provide a relatively stiff crush proof box for carrying cigarettes and both provide a swingable cover integrally connected to the body of the box for exposing the upper ends of the cigarettes packed therein. Both boxes provide selectively 45 operable folding ash receptacle and cigarette snuffing chamber that can be opened and closed at the user's option without interfering with the normal cigarette holding and protectioning functions of the package.

The carton blank and insert blank shown in Figs. 2 and 3 can be assembled in a different manner to achieve the same functional properties of the erected box. As shown in Figs. 8 and 9, the front wall 3 and its side flaps 23 can be laid flat and the front insert panel 28 can be secured to the adhesive layers 38. The inner insert panel

27 is then folded back on the panel 28 and the side flaps 33 and 35 folded up. The side walls 8 of the back wall 1 are folded up and the front wall 3 with the upstanding insert side flaps 33 and 35 is folded back over the upstanding side walls 8. Strips of adhesive 60 on the reverse sides of the side walls 8 or the reverse sides of the insert side flaps 33, or both, fasten the inner panels 27 of the insert to the side walls 8. The outer side wall flaps 23 can be folded up against the outer sides of the side flaps 35 before or after the front wall 3 and the insert panels are folded back on the back and side walls. Areas of adhesive 61 and 62 at the top and bottom of the inner side wall flaps or the tops and bottoms of the outer side wall flaps 23, or both, coat to hold the front wall 3 and outer receptacle panel closed till the frangible connection along the fold lines 241 is broken. After the pack is opened and the frangible connection broken, the flaps 35 slide between the side walls 23 and the side flaps 33 as the ash receptacle is opened and closed.

What is claimed as new is:

1. A package for cigarettes comprising an outer carton having front, back, top, bottom and side walls comprising an integral blank having inner side wall flaps along the side edges of the back wall with said inner side wall flaps being slit along downwardly inclined lines near the upper edge thereof, bottom flaps hingedly secured to the lower edges of said inner side wall flaps and disposed alongside of said bottom wall, the bottom wall being hingedly connected to the bottom of the back wall and the bottom of a front wall, outer side wall flaps connected to the sides of said front wall by frangible and foldable connections, the top edges of said outer side wall flaps in the erected position of the carton being inclined correspondingly to the incline of the inner side wall flaps, cover forming flaps attached to the upper end of said back wall and to said top wall, an insert consisting of an integral blank having inner and outer front walls hingedly connected at the bottom, side flaps on the sides of said inner and outer insert walls, said insert blank having a fireproof coating and said side flaps on said insert walls being folded into opposed lapped relation and positioned within the inner side wall flaps on said carton blank, the outer wall and side flaps on the outer front wall of said insert being shorter than the inner wall and side flaps on the inner wall of the insert and terminating below the upper ends thereof, the inner side wall flaps of said carton blank being secured to the projecting portions of the said flaps on the inner wall of said insert, the upper edge of the outer wall of said insert in the erected position of the package having a cigarette receiving notch cut therein and projecting above the top of the front wall of said carton blank.

2. A package for cigarettes comprising an outer carton having front, back, top, bottom and side walls comprising an integral blank having inner side wall flaps along the side edges of the back wall with said inner side wall flaps being slit along lines near the upper edge thereof, bottom flaps hingedly secured to the lower edges of said inner side wall flaps and disposed along side of said bottom wall, the bottom wall being hingedly connected to the bottom of the back wall and the bottom of a front wall, outer side wall flaps connected to the sides of said front wall by frangible and foldable connections, cover forming flaps attached to the upper end of said back wall and to said top wall, an insert consisting of an integral blank having inner and outer front walls hingedly connected at the bottom, side flaps on the sides of said inner and outer insert walls, said insert blank having a fireproof coating and said side flaps on said insert walls being folded into opposed lapped relation and positioned within the inner side wall flaps on said carton blank, the side flaps on the outer front wall of said insert being shorter than the side flaps on the inner wall of the insert and terminating below the upper ends thereof, the inner side wall flaps of said carton blank being secured to the projecting portions of the side flaps on the inner wall of said insert, the upper edge of the outer wall of said insert in the erected position of the package having a cigarette receiving notch cut therein.

5 being secured to the projecting portion of the side flaps on the inner wall of said insert, the upper edge of the outer wall of said insert in the erected position of the package projecting above the top of the front wall of said carton blank.

10 3. A package for cigarettes comprising an outer carton having front, back, top, bottom and side walls comprising an integral blank having inner side wall flaps along the side edges of the back wall with said inner side wall flaps being slit along downwardly inclined lines near the upper edge thereof, bottom flaps hingedly secured to the lower edges of said inner side wall flaps and disposed along side of said bottom wall, the bottom wall being hingedly connected to the bottom of the back wall and the bottom of the front wall, outer side wall flaps connected to the sides of said front wall by frangible and foldable connections, the top edges of said outer side wall flaps in the erected position of the carton being inclined correspondingly to the incline of the inner side wall flaps,

20 flaps, cover forming flaps attached to the upper end of said back wall and to said top wall, an insert consisting of an integral blank having inner and outer front walls hingedly connected at the bottom, side flaps on the sides of said inner and outer insert walls, said insert blank having a fireproof coating and said side flaps on said insert walls being folded into opposed lapped relation and positioned within the inner side wall flaps on said carton blank, the side flaps on the outer front wall of said insert being shorter than the side flaps on the inner wall of the insert and terminating below the upper ends thereof, the inner side wall flaps of said carton blank being secured to the projecting portions of the side flaps on the inner wall of said insert, the upper edge of the outer wall of said insert in the erected position of the package having a cigarette receiving notch cut therein.

25 4. A package for cigarettes comprising an outer carton having front, back, top, bottom and side walls comprising an integral blank having inner side wall flaps along the side edges of the back wall, the bottom wall being hingedly connected to the bottom of the back wall and the bottom of the front wall, outer side wall flaps connected to the sides of said front wall by frangible and foldable connections, cover forming flaps attached to the upper end of said back wall and to said top wall, an insert consisting of an integral blank having inner and outer front walls hingedly connected at the bottom, side flaps on the sides of said inner and outer insert walls, said insert blank having a fireproof coating and said side flaps on said insert walls being folded into opposed lapped relation and positioned within the inner side wall flaps on said carton blank, the side flaps on the outer front wall of said insert being shorter than the side flaps on the inner wall of the insert and terminating below the upper ends thereof, the inner side wall flaps of said carton blank being secured to the projecting portions of the side flaps on the inner wall of said insert, the upper edge of the outer wall of said insert in the erected position of the package having a cigarette receiving notch cut therein.

30 5. A package for cigarettes comprising an outer carton having front, back, top, bottom and side walls comprising an integral blank having first side wall flaps along the side edges of the back wall, the bottom wall being hingedly connected to the bottom of the back wall and the bottom of the front wall, other side wall flaps connected to the sides of said front wall by frangible and foldable connections, cover forming flaps attached to the upper end of said back wall and to said top wall, an insert consisting of an integral blank having inner and outer front walls hingedly connected at the bottom, side flaps on the sides of said inner and outer insert walls, said insert blank having a fireproof coating and said side flaps on said insert walls being folded into opposed lapped relation and positioned within the first side wall flaps on said carton blank, the side flaps on the outer front wall

of said insert being shorter than the side flaps on the inner wall of the insert and terminating short of the upper and lower ends thereof, the first side wall flaps of said carton blank being secured to the projecting portions of the said flaps on the inner wall of said insert above and below the ends of the side flaps on the outer front wall of the insert.

6. A package for cigarettes comprising an outer carton having front, back, top, bottom and side walls comprising an integral blank having first side wall flaps along the side edges of the back wall, the bottom wall being hingedly connected to the bottom of the back wall and the bottom of the front wall, other side wall flaps connected to the sides of said front wall by frangible and foldable connections, cover forming flaps attached to the upper end of said back wall and to said top wall, an insert consisting of an integral blank having inner and outer front walls hingedly connected at the bottom, side flaps on the sides of said inner and outer insert walls, said insert blank having a fireproof coating and said side flaps on said insert walls being folded into opposed lapped relation and positioned within said carton blank, the side flaps on the other front wall of said insert being shorter than the side flaps on the inner wall of the insert and terminating short of the upper and lower ends thereof, the side wall flaps of said carton blank being secured to the projecting portions of the said flaps on the inner wall of said insert above and below the ends of the side flaps on the outer front wall of the insert.

7. A package for cigarettes comprising a carton having front, back, top, bottom and side walls comprising an integral blank having first side wall flaps along the side edges of the back wall the bottom wall being hingedly connected to the bottom of the back wall and the bottom of the front wall, cover forming flaps attached to the upper end of said back wall and to said top wall, an insert consisting of inner and outer front walls hingedly connected at the bottom, side flaps on the sides of said inner and outer insert walls, said insert having a fireproof coating and said side flaps on said insert walls being folded into opposed lapped relation and positioned within the first side wall flaps on said carton blank, the side flaps on the outer front wall of said insert being shorter than the side flaps on the inner wall of the insert and terminating short of the ends thereof, the first side wall flaps of said carton blank being secured to the projecting portions of the said flaps on the inner wall of said insert.

8. A package for cigarettes comprising a carton having front, back, top, bottom and side walls comprising an integral blank having first side wall flaps along the side edges of the back wall, the bottom wall being hingedly connected to the bottom of the back wall and the bottom of the front wall, cover forming flaps attached to the upper end of said back wall and to said top wall, an insert consisting of inner and outer front walls hingedly connected at the bottom, side flaps on the sides of said inner and outer insert walls, said side flaps on said insert walls being folded into opposed lapped relation and positioned within side wall flaps on said carton blank, the side flaps on the outer front wall of said insert being shorter than the side flaps on the inner wall of the insert and terminating short of one end thereof, the side wall flaps of said carton blank positioned outside said insert being secured to the projecting portions of the side flaps on the inner wall of said insert.

9. In a cigarette box, the combination of a back wall with side wall flaps hingedly connected to the sides thereof, cover forming flaps and walls hingedly connected to each other and to the top of said back wall, a bottom wall hingedly connected to the bottom of said back wall, a front wall hingedly connected to the front edge of said bottom wall, an outer receptacle wall secured in lapped relation to the inside of said front wall, an inner receptacle wall positioned in lapped relation to the inside

of said outer receptacle wall and hingedly connected thereto at the bottom edges of the walls, means located at the upper edges of said outer receptacle wall and said front wall forming a cigarette receiving notch, side flaps 5 on the sides of said inner and outer receptacle walls disposed in lapped relation to each other and to the inside of the side flaps on said back wall, the side flaps on said outer receptacle wall terminating short of the upper and lower ends of the side flaps on the inner receptacle wall and the side wall flaps on the back wall being in lapped secured relation to the projecting ends of the flaps on said inner receptacle wall.

10. In a cigarette box, the combination of a back wall with side wall flaps hingedly connected to the sides thereof, cover forming flaps and walls hingedly connected to each other and to the top of said back wall, a bottom wall hingedly connected to the bottom of said back wall, a front wall hingedly connected to the front edge of said bottom wall, an outer receptacle wall secured in lapped relation to the inside of said front wall, an inner receptacle wall positioned in lapped relation to the inside of said outer receptacle wall, side flaps on the sides of said inner and outer receptacle walls disposed in lapped relation to each other and to the side flaps on said back wall, the side flaps on said outer receptacle wall terminating short of one end of the side flaps on the inner receptacle wall and the side wall flaps on the back wall being in lapped secured relation to the projecting ends of the flaps on said inner receptacle wall.

30 11. In a cigarette package the combination of hingedly connected front, back and bottom walls, side flaps on the side edges of said front and back walls, the front wall being connected to the side flaps thereon by frangible connections, inner and outer receptacle forming panels 35 hingedly connected at the bottom and disposed in lapped relation with the outside of the outer panel secured to the back of said front wall, and side flaps on said receptacle forming panels folded into lapped relation with each other and with the side flaps on said front and back 40 walls, the side flaps on said outer receptacle forming panel having cut away portions at the top and bottom exposing the adjacent areas of the side flaps on said inner receptacle forming panel, said side flaps on said receptacle forming panels being disposed within the side flaps on said back wall with the side flaps on said back wall 45 secured to the side flaps on said inner receptacle forming panel at the areas exposed by said cut away portions.

12. In a cigarette package the combination of hingedly connected front, back and bottom walls, side flaps on the side edges of said front and back walls disposed in inner and outer lapped relation on said package, the front wall being connected to the side flaps thereon by frangible connections, inner and outer receptacle forming panels hingedly connected at the bottom and disposed in lapped 55 relation with the outside of the outer panel secured to the back of said front wall, and side flaps on said receptacle forming panels folded into lapped relation with each other and with the side flaps on said front and back walls, the side flaps on said outer receptacle forming panel having cut away portions exposing the adjacent areas of the side flaps on said inner receptacle forming panel, the outermost side flaps on said walls being secured to the side flaps on said inner receptacle forming panel at the areas exposed by said cut away portions.

60 13. In a cigarette package the combination of hingedly connected back, front and bottom walls, side flaps on the side edges of said back walls, inner and outer receptacle forming panels hingedly connected at the bottom and disposed in lapped relation to each other with the outer side of the outer panel secured to the inside of said front wall, and side flaps on said receptacle forming panels disposed in lapped relation within the side flaps on said back wall, the side flaps on the outer receptacle forming panel having cut away portions exposing the side flaps 65 on the inner receptacle forming panel and the side flaps

on said back wall and said inner panel being secured together at these exposed portions.

14. In a cigarette package the combination of hingedly connected back and bottom walls, side flaps on the side edges of said back wall, inner and outer receptacle forming panels hingedly connected at the bottom and disposed in lapped relation to each other, and side flaps on said receptacle forming panels disposed in lapped relation within the side flaps on said back wall, the side flaps on the outer receptacle forming panel having cut away portions exposing the side flaps on the inner receptacle forming panel and the side flaps on said back wall and said inner panel being secured together at these exposed portions.

15. In a cigarette package having a swingable top and a bottom the combination comprising a front wall, and

a back wall, inner and outer receptacle forming panels hinged together at the bottom and disposed at the inner side of said front wall, side flaps on said receptacle panels disposed in lapped relation and arranged perpendicularly between said walls, the flaps on the outer panel being shorter than the flaps on the inner panel and exposing areas at the ends of the inner flaps, and side flaps connected to the sides of said back wall and secured to the exposed areas of said flaps on said inner panel with the side flaps on the outer panel slidably positioned between the secured portions of the flaps.
